UNITED STATES PATENT OFFICE.

GEORGE ALVAH N. COPPEDGE, OF SANFORD, NORTH CAROLINA.

DRY CLOSET.

1,119,574.

Specification of Letters Patent.

Patented Dec. 1, 1914.

Application filed July 6, 1914. Serial No. 849,218.

To all whom it may concern:

Be it known that I, GEORGE A. N. COPPEDGE, a citizen of the United States, residing at Sanford, in the county of Lee and State of North Carolina, have invented a new and useful Dry Closet, of which the following is a specification.

The invention relates to improvements in dry closets.

10 The object of the present invention is to improve the construction of dry closets, more especially that shown and described in Patent No. 1,067,097, granted to me July 8, 1913, and to provide a simple, practical and inexpensive dry closet of strong and durable construction, equipped with an automatically closable lid adapted to be maintained in an open position by leg pressure while occupying the seat, and by foot pressure 20 in leaving the seat, whereby the lid is prevented from automatically closing and striking a person.

Another object of the invention is to enable the lid to be raised and held open by the foot when it is not desired to occupy the seat, and while removing the contents.

With these and other objects in view the invention consists in the construction and novel combination of parts hereinafter 30 fully described, illustrated in the accompanying drawing, and pointed out in the claims appended hereto, it being understood that various changes in the form, proportion, size and minor details of construction, 35 within the scope of the claims, may be resorted to without departing from the spirit or sacrificing any of the advantages of the invention.

In the drawing: Figure 1 is a perspective 40 view of a dry closet constructed in accordance with this invention and shown open. Fig. 2 is a central vertical sectional view of the same, the lid being shown closed in full lines and open in dotted lines. Fig. 3 is a 45 horizontal sectional view on the line 3—3 of Fig. 2. Fig. 4 is a detail perspective view of the upper portion of the removable inner receptacle.

Like numerals of reference designate corresponding parts in all the figures of the drawing.

In the accompanying drawing, in which is illustrated the preferred embodiment of the invention, 1 designates an outer cylindrical portable casing or receptacle designed to be constructed of galvanized iron or other

suitable material. The upper edge 2 of the casing or receptacle 1 is also preferably reinforced or stiffened with wire, which is arranged in a bead in the usual manner. The outer casing is equipped at the top with a seat 3, preferably constructed of wood and hinged at the back at 4 to a removable supporting member 5, preferably constructed of galvanized sheet metal, and provided with an opening 6, corresponding with the seat opening 7. The supporting member, which is inclined downwardly and inwardly from the walls of the outer receptacle or casing 1 to the openings 6 for directing liquid matter into an inner removable receptacle 8, is provided at its outer portion with an upwardly extending vertical flange 9, and an outwardly extending horizontal flange 10. This inclined portion of the supporting member is arranged at an angle to the horizontal lower face of the seat, and provides an intervening space between the seat and the supporting portion, which is in contact with the seat only at the outer edge 80 thereof. The horizontal flange 10 is arranged upon the upper edge of the outer casing or receptacle and the vertical flange 9, which fits against the inner face of the outer casing or receptacle 1, extends into the same 85 to arrange the inclined body portion of the supporting member below the plane of the upper edge of the outer casing. The seat is supported slightly above and out of contact with the upper face of the supporting member 5 by buffers 11, of rubber or other suitable material, forming projections which extend from the lower face of the seat. The buffers 11 are adapted to cushion the seat in its contact with the supporting member, and 90 eliminate noise in dropping the seat from a raised position. The spacing of the seat from the upper face of the supporting member is for the purpose of permitting the latter to drain. The flanged supporting member forms a recess to receive the seat, which also extends into a recess of a lid or cover 12. The lid or cover 12, which is connected at the back with the outer casing 1 by an exterior hinge 13, is designed to be constructed 105 of galvanized sheet metal or other suitable material, and is provided with a downwardly extending vertical flange 14 and an outwardly extending horizontal flange 15, which rests upon the outwardly projecting flange 10 of the supporting member 5. The lid or cover and the supporting member

form a space in which the seat is received, as clearly shown in Fig. 2 of the drawing. The lid or cover, when open, is arranged in a slightly inclined position, and extends upwardly and forwardly from the back of the casing, and it is adapted to close automatically when free to move. The lid or cover, which may be conveniently opened by a pedal or foot plate 16, is maintained in an open position by mechanism arranged to receive pressure from a person occupying the seat. The mechanism comprises in its construction a pair of side levers 17 constructed of suitable metal and fulcrumed at a point intermediate of their ends on terminal projecting portions 18 of a horizontal supporting bar 19, curved between the terminal portions 18 to fit the outer casing 1 and riveted or otherwise secured to the same. The terminal portions 18, which are straight, have their ends bent rearwardly at right angles to form ears 20, to which the levers are pivoted by pins 21 piercing the ears and the levers and provided with cotter pins 22. The levers, which may be pivoted to the supporting bar in any other desired manner, are connected at their rear arms with the hinged lid of a pair of straight links 23 pivoted at their lower ends to the rear terminals of the side levers 17 by rivets 24 or other suitable fastening device, and also connected at their upper ends by suitable pivots 25 with ears 26 of an upper transverse connecting bar 27 riveted or otherwise secured to the upper or outer face of the lid or cover and projecting laterally from opposite sides thereof. The terminals of the upper transverse connecting bar 27 are bent at right angles to form the ears 26, which extend downwardly when the lid or cover is in its closed position. When the lid or cover is bent, it carries with it the side links 23, which swing the rear arms of the side levers 17 upwardly during such opening movement. The front arms of the said levers are swung downwardly by the opening movement of the lid or cover, and they are connected by a lower transverse bar 28, having its terminals bent downwardly at right angles to form ears 29, which are pivoted to the front ends of the side levers 17 by rivets 30 or other suitable fastening devices. The lower connecting bar, which is of the same length as the upper connecting bar, is of a similar construction, and it is connected at its center with a vertical bar 31 provided intermediate of its ends with right angle bends forming an intermediate horizontal portion 32, which is secured to the lower connecting bar at the upper face thereof by a rivet 33 or other suitable fastening means. The vertical bar 31 is slidable downwardly and upwardly through a guide 34, and carries a horizontal leg receiving bar 35. The upper end 36 of the vertical bar 31 is bent rear-

wardly at right angles to form a leg or ear which is centrally secured to the leg receiving bar 35 at the lower face thereof. The terminal portions of the leg receiving bar are supported by oppositely inclined braces 37, preferably constructed of a single piece of metal and connected at their lower ends by a horizontal portion 38, which is secured to the upper face of the lower connecting bar 28 by a rivet 33. The horizontal connecting portion 38 is interposed between the horizontal portion of the vertical bar 31 and the lower connecting bar 28. The upper terminals of the inclined braces 37 are bent outwardly at right angles to form attaching lugs or ears 39, and the fastening means for securing the lugs or ears 36 and 39 to the lower face of the leg receiving bar 35 terminates short of the upper face thereof. The guide 34, which is constructed of suitable metal, extends rearwardly from the outer casing 1 and it consists of an approximately rectangular loop composed of spaced sides and a connecting outer portion, the terminals of the metal being extended laterally in opposite directions at the inner ends of the said sides to form attaching portions 40 which are riveted or otherwise secured to the said outer casing 1. The sides of the guide are connected at an intermediate point by a cross piece 41, suitably secured to the said sides and arranged in spaced relation with the said transverse connecting portion of the loop to form a guide opening to receive the vertical bar 31. The leg receiving bar 35, which extends laterally from the upper end of the vertically slidable bar 31, is located in an elevated position above the casing 1 when the lid or cover is closed, as illustrated in Fig. 2 of the drawing, and the opening movement of the lid or cover lowers the horizontal leg receiving bar 35 to the guide 34. In this position the horizontal leg receiving bar is located substantially in the plane of the upper face of the seat, and is adapted to extend beneath the legs of the occupant, whereby it will be subjected to pressure for maintaining the lid or cover in its open position. The horizontal guide 34 forms a support for the leg receiving bar and limits the downward movement thereof and the consequent opening movement of the lid or cover, which is thereby maintained at a forward inclination when in its open position to cause a positive automatic closing of the lid or cover when the vertical bar is free to move upwardly. The feet may also be placed on the lower transverse connecting bar 28 and the pressure exerted thereon will also operate to prevent the lid or cover from closing. The lower portion 42 of the vertical bar 31 depends from the lower connecting bar and carries the treadle or foot plate 16, which is connected at its rear por-

tion with the lower end of the vertical bar by being formed integral therewith, or in any other desired manner. The foot plate or pedal is adapted to be depressed by the 5 operator, and it rests upon the floor when the lid or cover is in its open position. The foot plate or pedal, in engaging the floor, cooperates with the guide 34 in forming a stop to limit the opening movement of the lid or 10 cover. As soon as the mechanism connected with the lid or cover is relieved of pressure, the lid or cover will close automatically through the action of gravity. The foot plate or treadle not only forms a convenient 15 means for opening the lid or cover, but enables the same to be readily held in an open position by a person in leaving the seat, so that the hinged lid or cover will not automatically close and strike a person.

20 The inner receptacle 8, which is of greater diameter than the seat opening 7, extends from the bottom of the casing to within a short distance of the seat. The inner receptacle, which is equipped with a bail 43, is 25 provided at its upper edge with an outwardly extending horizontal annular flange 44, adapted to support a removable lid or cover 45. The lid or cover 45, which preferably consists of a flat disk, is provided 30 at its lower face with a yieldable gasket 46, adapted to fit against the upper face of the horizontal flange 44 to form an air tight joint to prevent the escape of odors when the inner receptacle is removed from the 35 casing 1. The lid or cover 45 is tightly secured on the flange 44 by clamping bars or members 47, arranged in pairs at opposite sides of the lid or cover 45 and pivoted to the same by rivets 48 which also fasten a 40 handle 49 to the said lid or cover 45. The terminal portions of the clamping bars 47 are bent downwardly and inwardly, and the pivots or rivets 48 are arranged eccentrically with relation to the lid or cover 45. 45 When the clamping bars or members 47 are extended in substantial alinement with the handle 49, their outer engaging portions 50 are carried beyond the flange 44 and the lid or cover 5 may then be readily placed on 50 and removed from the inner receptacle 8. The clamping bars or members 47 are carried into engagement with the flange 44 by swinging them apart and arranging them at an angle to each other and to the handle 55 49, as clearly shown in Fig. 4 of the drawing. The inner receptacle may then be lifted and carried by the handle 49, which is angularly bent between its ends to offset from the lid or cover 45 the portion to be gripped 60 by the hand.

The dry closet, which may be used in any room or apartment, is provided at the back with a ventilating pipe 51, provided at its lower end with an elbow 52, which is connected with a nipple 53 projecting from the

back of the casing 1 at a point below the hinged lid or cover. The casing is provided at the vent pipe with an interior screen 54, and it is equipped at the back with an exterior bracket 55 of substantially L-shape, 70 consisting of an approximately vertical arm and a rearwardly projecting arm arranged at a slight inclination and adapted to form a stop or seat for the hinged lid or cover 12, as clearly illustrated in dotted lines in 75 Fig. 2 of the drawing. The bracket 55 is also provided in its rearwardly projecting portion with an opening 55^a for the reception of a wire 56 or other suitable fastening means for securing the vent pipe to the 80 bracket, whereby the vent pipe is firmly maintained in an upright position and is prevented from becoming accidentally disconnected from the outer casing when the dry closet is subjected to more or less rough 85 usage. The ventilating pipe, which operates in the usual manner to carry away the odors from the dry closet, is designed to extend through the roof or to any other point exterior of the room or apartment in which 90 the dry closet is placed. When the lid or cover is closed, flies and other insects are effectually excluded from the interior of the casing. The inner receptacle is equipped with a bag or container 57, constructed of 95 oiled paper or other suitable material, and of a size to fit the interior of the inner receptacle 8. The bag or container, which is of a length greater than the inner receptacle, is adapted to have its upper portion or edge 58 folded back from the upper edge of the inner receptacle. The inner bag or container enables the contents of the inner receptacle to be readily removed. As the wooden seat is of a thickness greater 100 than the depth of the recess of the supporting member 6, a person using the seat will not come in contact with the metal of the outer casing, and the leg receiving bar 35 cooperates with the seat to support the legs out 105 of contact with the upper edge of the outer casing.

What is claimed is:—

1. A dry closet including a casing, a seat of less diameter than the casing having an 115 opening, a supporting member receiving and constituting the sole support of the seat and flanged at its periphery to rest upon the upper edge of the casing, and provided with an opening corresponding with the seat opening, said supporting member being inclined 120 downwardly and inwardly from the walls of the outer casing to its opening and arranged at an angle to the lower face of the seat.

2. A dry closet including a casing, a supporting member arranged within the upper portion of the casing and provided at its periphery with an upwardly extending flange and also with an outwardly extending flange, the latter being supported upon the upper 130

edge of the casing, said supporting member having an opening, a seat mounted upon the said supporting member and arranged within the upwardly extending flange thereof, and a lid or cover provided at its periphery with a downwardly extending flange to form a recess into which the seat extends, said lid or cover being also provided with an outwardly extending flange arranged upon the outwardly extending flange of the supporting member and the seat being entirely inclosed when the lid or cover is closed.

3. A dry closet including a casing, a lid or cover hinged to the casing at the back thereof, a vent pipe also connected with the back of the casing, a bracket secured to the back of the casing and having a projecting portion forming a stop for the lid or cover, and means for securing the vent pipe to the projecting portion of the bracket.

4. A dry closet including a portable casing having a seat, an automatically closable lid hinged to the casing, a pair of levers fulcrumed intermediate of their ends at opposite sides of the casing to form front and rear arms and carried by the said casing, means for connecting the rear arms of the levers with the lid, and a front foot piece or pedal connected with the front arms of the levers and arranged to rest upon the floor when the lid is open, whereby the lid may be maintained in such open position by standing on the foot plate or pedal.

5. A dry closet including a portable casing having a seat, an automatically closable lid hinged to the casing, a pair of levers fulcrumed intermediate of their ends at opposite sides of the lower portion of the casing to form front and rear arms and carried by the said casing, links located at opposite sides of the casing and connecting the rear arms of the levers with the lid, a front transverse bar connecting the front arms of the levers, and a foot plate or pedal carried by the front connecting bar and arranged to rest upon the floor when the lid is open, so that the lid may be maintained in an open position by standing upon the foot plate or pedal.

50 6. A dry closet including a portable casing having a seat, an automatically closable lid hinged to the casing, a pair of levers fulcrumed intermediate of their ends at oppo-

site sides of the lower portion of the casing to form front and rear arms and carried by the said casing, links located at opposite sides of the casing and connecting the rear arms of the levers with the lid, a front transverse bar connecting the front arms of the levers, a vertically movable bar secured to the front transverse bar and extending upwardly and downwardly therefrom, leg receiving means carried by the upper end of the vertically movable bar, and a pedal or foot plate extending from the lower end of the vertically movable bar and arranged to rest upon the floor when the lid is open, so that the lid may be maintained in an open position by standing upon the foot plate or pedal.

7. A dry closet including a portable casing having a seat, an automatically closable lid hinged to the casing, a pair of levers fulcrumed intermediate of their ends at opposite sides of the lower portion of the casing to form front and rear arms and carried by the said casing, links located at opposite sides of the casing and connecting the rear arms of the levers with the lid, a front transverse bar connecting the front arms of the levers, a vertically movable bar secured to and extending upwardly from the front connecting bar and having a central foot plate or pedal limited in its downward movement by the floor, whereby the lid may be maintained in an open position by standing upon the foot plate or pedal, a leg receiving bar carried by the upper end of the vertically movable bar and extending laterally from opposite sides thereof, and opposite braces connecting the terminal portions of the leg receiving bar with the front connecting bar and having a connecting portion contiguous to the vertically movable bar and the front connecting bar, and a fastening device piercing the vertical bar, the connecting portion of the braces, and the front connecting bar, and securing the said parts together.

In testimony, that I claim the foregoing as my own, I have hereto affixed my signature in the presence of two witnesses.
